ELECTRICAL PROBE FOR A RESISTOR-METER

Yoshiharu Alan Shimasaki, 5-12, 3-chome, Minami-Azabu, Minato-ku, Tokyo, Japan

Filed Feb. 28, 1968, Ser. No. 10,765

Claims priority, application Japan Aug. 31, 1967

Term of patent 14 years

Int. Cl. D10—10

U.S. Cl. D26—1

FIG. 3

FIG. 2

FIG. 1 is a front view of the electrical probe for a resistor-meter, embodying my new design;

FIG. 2 is a perspective view taken from left end of FIG. 1;

FIG. 3 is a sectional view taken along lines 3—3 of FIG. 1.

The cable portion is shown broken away in FIG. 1 to indicate indeterminate length.

I claim:

The ornamental design for an electrical probe for a resistor-meter, as shown and described.
